UNITED STATES PATENT OFFICE.

HALWARD G. WESTMORE, OF MILWAUKEE, WISCONSIN, ASSIGNOR, BY MESNE ASSIGNMENTS, TO A. O. SMITH CORPORATION, OF MILWAUKEE, WISCONSIN, A CORPORATION OF NEW YORK.

SPRING-HANGER.

1,323,561.

Specification of Letters Patent.

Patented Dec. 2, 1919.

Application filed December 22, 1916. Serial No. 138,345.

To all whom it may concern:

Be it known that I, HALWARD G. WESTMORE, citizen of the United States, residing at Milwaukee, county of Milwaukee, and 5 State of Wisconsin, have invented new and useful Improvements in Spring-Hangers, of which the following is a specification.

My invention relates to improvements in spring hangers for the side bars of motor 10 driven vehicle frames. In ordinary practice, the side bars of motor driven vehicle frames are substantially U-shaped in cross-section and the spring hangers are usually formed with a shank to fit within the front 15 end of the side bar and riveted to the vertical web connecting the top and bottom flanges of the bar. The shank extends beyond the end of the bar and is provided with an apertured head to receive a connecting 20 bolt to which the front end of the spring is coupled. It has also been customary heretofore to form the head with a projecting shoulder with which the end of the frame 25 bar is brought into substantially abutting contact when the parts are assembled. But it has been found, in practice, that the ends 30 of the side bars are more or less irregular in form and to avoid the expense of machining the opposing faces of the extremity of the bar and the shoulder on the head, it has been customary to assemble the parts with only 35 approximate contact between the shoulder and the irregular end of the bar, leaving gaps to be filled with paint or putty, which frequently breaks away after the vehicle has 40 been in use for a short time, thereby exposing an unsightly seam and marring the appearance of the vehicle.

The object of my invention is to overcome 45 the above mentioned difficulties and also to add to the strength of the joint between the hanger and the frame bar by providing means whereby the hanger overlaps the outer surface or surfaces of the frame bar 50 and whereby the overlapping portion of the hanger may clampingly engage the end portion of the frame bar upon at least three sides thereof.

In the drawings—

55 Figure 1 is a view of the front end portion of a removable frame bar provided with my improved spring hanger as viewed from the inner side.

Fig. 2 is a plan view of the same.

Like parts are identified by the same reference characters in both views. 55

My improved hanger is provided with a shank A adapted to fit within the front end portion B of the frame bar in the ordinary manner and connected therewith by rivets 60 C in accordance with common practice. The head D of the hanger is also of ordinary construction, except that the shouldered portion E is provided with an overhanging bead F, which projects from and embraces 65 the top, bottom and side flanges of the frame bar, as clearly shown in Fig. 1. In constructing the hanger, sufficient space is left between the overhanging bead F and the portion of the shank A, which it incloses, 70 to allow the extremity of the side bar B to freely enter such spaces, after which, the bead F may pass inwardly in clamping relation to the outer surface of the side bar, against which it bears on three sides, thereby 75 securely clamping the head to the extremity of the frame bar, and not only avoiding an open seam or joint, but also preventing relative vibration of these parts such as would otherwise cause the paint and varnish to crack or break away. 80

With the above described construction, it is not only unnecessary to secure actual abutting contact between the extremity of the frame bar B and the shoulder E, but it 85 is also unnecessary to fill the space or spaces between said shoulder and the extremity of the bar with putty or other material, since the joint is concealed by the overlapping bead F. 90

The side bars of motor driven vehicle frames are formed from sheet metal, pressed into the desired shape and their outer surfaces are sufficiently flat and smooth so that it is not difficult to press the bead F of the 95 hanger into clamping relation thereto and into substantially continuous contact with the surfaces of the bar at all points.

I claim:—

1. A spring hanger for the side bars of 100 motor driven vehicle frames, including a shank provided with a head having a channel adapted to receive the end margins of the frame bar;—said head being provided with an overhang bead comprising the outer wall 105 of the channel and adapted to bear upon the outer surfaces of the frame bar, whereby the end margins of the bar may be engaged

between said bead and the shank in close fitting relation thereto.

2. The combination with the side bar of a motor driven vehicle frame, of a spring hanger having a channel to receive the ends of the walls of the side bar, and a shank projecting into and connected with the bar.

3. The combination with the channeled side bar of a motor driven vehicle frame, of a spring hanger having a channel to receive the ends of the walls of the side bar, with the exterior wall of said channel embracing the top, bottom and side surfaces of the bar in clamping relation thereto.

15 4. The combination with the channeled side bar of a motor driven vehicle frame, of a spring hanger provided with a shank secured to the inner face of the bar near one end thereof, and also having a portion embracing the outer surfaces of the top, bottom and side walls of the bar adjacent to said end thereof.

5. The combination with the channeled side bar of a motor driven vehicle frame, of

a spring hanger provided with a shank extending into the channel of the side bar and secured therein, the spring hanger being also provided with an overlapping portion embracing the ends of the walls of the channeled side bar and clamping such ends to the shank of the spring hanger.

25 6. The combination with the channeled side bar of a motor driven vehicle frame, of a spring hanger having a shank extending into the channel of the side bar and secured therein, the said spring hanger also having an overlapping beaded portion embracing the walls of the channeled side bar at one end thereof and clamping such walls between the overlapping portion and the shank of the spring hanger.

35 35 In testimony whereof I affix my signature in the presence of two witnesses.

HALWARD G. WESTMORE.
